UNITED STATES PATENT OFFICE

TOMLINSON FORT JOHNSON, JR., OF ATLANTA, GEORGIA

DISCONNECTING AIR-BREAK SWITCH

Application filed June 4, 1925. Serial No. 34,879.

This invention relates to an improved disconnecting switch of the air break type adapted to be used on high tension lines, and particularly to an automatically operated trip 5 device for opening the same when a heavy overload or short circuit occurs on the line.

The general object of the invention is to provide an air break switch which is adapted to be operated in a gang, which is simple in 10 its construction and efficient in its operation, which may be manufactured and sold at a comparatively low price, and which may, in a great many instances, take the place of the more expensive oil switch now generally used, 15 thus effecting a considerable saving in capital expenditure.

The switch herein shown, with its automatic trip, is self-contained, needing no auxiliary source of operating current. All 20 metallic parts may be cast, thus reducing the manufacturing cost to a minimum. The operating handle may be moved in either direction to close the switch. Other features are rugged construction, a heavy pressure 25 contact, and quick movement of the blade in both directions.

The switch, which constitutes the present invention, is similar in many respects to the switch disclosed in my earlier application, 30 Serial No. 700,112, filed March 18, 1924, but embodies various improvements thereover.

The detailed construction of the present invention and its advantages will be more specifically explained in connection with the accompanying drawings, which illustrate the preferred form of the invention.

In the drawings:

Figure 1 is a plan view of a gang switch 40 constructed in accordance with the invention.

Figure 2 is a side elevation thereof, with parts broken away and shown in section.

Figure 3 is a vertical longitudinal section 45 through one of the switches and the parts associated therewith.

Figure 4 is a horizontal section taken on the line 4—4 of Figure 3.

Figure 5 is a section taken on the line 5—5 50 of Figure 3.

Figure 6 is a fragmentary section taken on the line 6—6 of Figure 3.

Figure 7 is a section taken on the line 7—7 of Figure 3.

In actual practice, the switches will usually 55 be operated in sets of three, called a gang, corresponding to the three conductors used in a three-phase alternating system. Each of these three switches is supported on a bar 10 at the top of a tower or pole of the transmission line. For this purpose, three insulators 11, 12 and 13 are mounted on the bar 10. The pin 14 of the insulator 11 is clamped to a transverse rod 15, which is journaled in a bracket 16 secured to the bar 10. The pin of 60 the insulator 12 is clamped in a casting 17, and is supported for rotation about a vertical axis. An arm 18 is secured to the casting 17 and extends horizontally above the bar 10, its outer end being connected to a transverse 65 rod 19, which is similarly connected to the arms 18 which are connected to the other insulators 12. The pin 20, which supports the insulator 13, is secured in fixed relation to the 70 bar 10.

Brackets 21, 22 and 23 are clamped to the upper ends of the respective insulators 11, 12 and 13. A yoke 24 is mounted above the insulators 11 and 12, and is formed above the latter with two spaced arms 25, the outer portions of which extend downwardly and meet in a plate or abutment 26, which rests on a boss 27 extending upwardly from the center of the bracket 22. A headed pin 28, anchored 75 in the boss 27, retains the plate 26 in its position on the bracket 22, but permits the latter to rotate with the insulator 12. The main part of the yoke 24 is supported from the insulator 11 by means hereinafter more particularly described, which allows the insulator to 80 be rocked longitudinally with the rod 15, while the yoke 24 is held against longitudinal movement by its connection with the pin 28.

A pin 29 is journaled transversely of the arms 25, and the switch blade 30 is secured 85 in fixed relation to the pin by a set screw 31 or the like. The switch blade 30 is of rugged construction, and its outer end is normally clamped between jaws 32, which are preferably mounted in the manner disclosed in my 90 100

earlier application above referred to, and which are electrically connected by loops 33 to the bracket 23, the latter being provided with a lug 34 adapted to receive the end of the line conductor 35. The switch blade 30 and the bracket 23 are preferably provided with horns 36 and 37, respectively, to prevent the formation of arcs between the switch blade and the jaws when the circuit is opened or closed.

10. The switch blade 30 has a rearwardly extending tail 38, the bottom and sides of which are encased in a shoe 39, pivotally mounted on the pin 29. A roller 40 normally engages the underside of the shoe 39, and positively 15 holds the tail 38 in its uppermost position with the switch blade 30 clamped between the jaws 32. The roller 40 is rotatably supported in a fork 41 carried by the end of a rod 42, which is slidably mounted in a lug 43 depending from the yoke 24, while the fork 41 rests on a roller 44 mounted in arms 45, depending from the yoke 24.

15. A hood 46 is secured to the yoke 24, and above this hood is secured a bracket 47 with upwardly projecting arms 48 between which a sleeve 49 is pivoted. A barrel 50 is clamped within the sleeve 49, the rear end of which is split and secured to the barrel by a clamping bolt 51. The sleeve 49 has a forwardly 20 projecting reduced portion 52 in which a rod 53 is slidably mounted. A head 54 is secured to the rear end of the rod 53 within the barrel 50, and an expansile coiled spring 55 is housed within the barrel 50, and acts between the head 54 and the forward portion of the sleeve 49. A hood 56 covers the rod 53, and the forward end of the latter is secured to a connecting member 57 which is connected to a pivot pin 58, the front end of the hood 56 being also connected to the pivot pin. A cam 59 has an upwardly projecting tongue, which is pivoted to the pin 58 between the ears of the connecting member 47, and this cam extends downwardly on opposite sides 25 of the blade 30 to which it is pivotally connected by a pin 60. Whenever the roller 40 is retracted, by means hereinafter described, and the tail 38 of the switch blade is free to moved downwardly, the spring 55, which is 30 under compression, moves the rod 53 rearwardly rocking the cam 59 about its pivot 60, so that the larger portion of the cam is brought into engagement with the abutment 26, forcing the blade 30 upwardly and out of engagement with the jaws 32.

35. In closing the switch, the insulator 12 and the bracket 22 are rotated about a vertical axis, and a cam 61, which projects from the bracket 22, engages the shoe 39 underneath the tail 38 of the switch blade to close the latter. After effecting this movement, the cam 61 is left in a position at one side of the switch blade, so that normally the roller 40 is the only means for retaining the switch blade in

its closed position. For convenience in rotating the insulator 12, a shaft 62 is secured in fixed relation to the insulator pin, and extends downwardly to the ground where its lower end may be rotatably supported in a concrete base 63, or other suitable bearing, and an operating handle 64 is removably connected to the shaft 62.

40. For the purpose of attaching suitable means for operating the rod 42 and retracting the roller 40 automatically, a disk 65 is secured to the rear end of the yoke 24, and an insulating block 66 is bolted to the rear face of this disk. A cylindrical casing 67 containing a solenoid is bolted to the rear face of the block 66, the coils of the solenoid being wound about an insulating sleeve 68 within which the core 69, which may be a fiber tube filled with wire, of the solenoid is mounted. The core 69 has an adjustable threaded connection with the rear end of the rod 42, and is held in adjusted position by a lock nut 70. A wing nut 71 is connected to the rear end of the core 69 by a bolt 72, or the like, and is insulated from the casing of the solenoid by an insulating bushing 73. The core 69 is insulated from the plate 65 to which one wire of the solenoid is connected and, since the wing nut 71 is insulated from the casing 67 to which the other wire of the solenoid is connected, the solenoid will not be short-circuited by the plunger. A collar 75 is threaded to the front part of the rod 42, and a coil spring 74, under compression, acts between the collar 75 and the lug 43 depending from the yoke 24 to hold the rod 42 and roller 40 normally in their forward positions until the current through the solenoid develops sufficient force to overcome the strength of the spring 74, to retract the roller 40 and release the switch blade. The forward movement of the roller is limited by a collar 76, adjustably secured to the plunger rod 42 and engageable with a bifurcated arm 77 extending upwardly from the bracket 21, and through which the rod 42 passes.

45. As explained above, the forward end of the yoke 24 is supported by the insulator bracket 22 in a manner which permits the rotation of said bracket, and yet prevents any movement of the yoke upwardly or downwardly, or longitudinally. The rear or main portion of the yoke 24 is supported from the insulator bracket 21 in a manner which permits said bracket and the insulator, which supports it, to rock with the transverse rod 15. The connection between the yoke 24 and the insulator bracket 21 includes a pin 78 extending transversely between two flanges 79 which depend from the yoke 24, and straddle a portion of the bracket 21, which is provided with a longitudinally disposed arcuate slot 80 for receiving the pin 78.

50. Under normal conditions, the insulator 11 is held in the position shown in Figures 2

and 3, being inclined toward the insulator 12 by reason of the engagement of the collar 76 with the bracket arm 77, the plunger 42 and collar 76 being impelled toward the insulator 12 by the spring 74. The movement of the insulator 11 in the direction of the insulator 12 is limited, however, by a pair of rods 81, the rear ends of which extend through holes in the bifurcated end of the arm 77, and have nuts 82 threaded thereon against which the bifurcated end of the arm 77 abuts. The front ends of the rods 81 are supported in elbows 83 having downturned ends which are journaled on pivot pins 84 supported in ears extending from sleeves 85, which are rigidly secured to the pivot pin 29 to which the switch blade 30 is secured.

The shoe 39 has forwardly projecting arms 86 with rounded ends which engage inclined ribs 87 formed on the sides of the cam 59, thus constituting a latch which prevents the rotation of the cam as long as the shoe is engaged by the roller 40. Whenever the roller 40 is retracted to release the blade, and the cam 59 begins to turn about the pivot 60, the blade is forced upwardly, rotating the pin 29 and sleeves 85, and lifting the pivot pins 84 upwardly about the pin 29 as an axis, thereby swinging the rods 81 rearwardly, and swinging the bracket 21 and insulator 11 away from the insulator 12. This results in the opening of all the other switches in the gang by reason of the connections which will now be described.

Each insulator 11 is clamped to a rod 15 as above explained. The rod 15 is rigidly secured to a disk coupling member 88, which, in turn, is rigidly secured to the rod 15 on which the next insulator 11 is secured. In this manner, all of the rods 15 and all of the insulators 11 are rigidly secured together, so as to rotate in unison. When one of the switch blades 30 is opened, therefore, the forward ends of the arms 86 are swung upwardly, thus swinging the rods 81 rearwardly. This swings the corresponding insulator 11, and likewise all of the other insulators 11, away from the corresponding insulators 12. The bracket 21 on each of these other insulators 11 engages the corresponding collar 76, thus moving the rod 42 and roller 40 to release the corresponding switch blade. Thus, it will be seen that whenever one of the switch blades is automatically opened by the action of its solenoid, all of the other switch blades in the gang will be opened.

In order that the switch blades may be opened manually whenever desired, one of the rod sections 15 has a laterally projecting arm 89 secured thereto, and a rod or pole 90 is connected to the outer end of the arm 89, so that by pulling the latter downwardly all of the insulators 11 will be simultaneous-

ly swung to open the corresponding switch blades.

For closing the switch blades, it will be noted that all of the arms 13, which are rigidly connected with the pins of the respective insulators 12, are connected to each other by a rod 19, so that by swinging the shaft 62, by means of the handle 64, all of the switch blades are closed simultaneously.

A lug 91, adapted to receive the end of the conductor 92 is connected to the solenoid within the casing 67, and the current passes through the solenoid and through the switch blade 30 and jaws 32 to the conductor 35. Whenever an excessive overload or a short circuit occurs on the line, it energizes the solenoid sufficiently to overcome the pressure of the spring 74 and to retract the roller 40 and release the switch blade. By loosening the lock nut 70 and rotating the core 69, by means of the wing nut 71, or by adjusting the collar 75 on the rod the compression on the spring 74 may be varied, so that the current at which the switch will open may be varied as conditions demand. The collar 75 is provided with a pointer 93, which operates with a scale 94, arranged adjacent thereto, to indicate an abnormal increase in amperage of the current passing through the solenoid.

From the foregoing description, it will be understood that all of the metallic parts of the trip mechanism may be made by casting, so that the cost of manufacture will be comparatively cheap. The switch may be produced for a small proportion of the cost of an oil switch. The core of the solenoid and the plunger rod are immediately responsive to changes in the current, and the switch will trip open instantaneously when the current passing through it reaches an abnormal amount.

The switch is adapted to be operated single, as well as in gangs. The automatic trip mechanism is, of course capable of general application, but it is preferred to use it in connection with a switch and pressure jaws of the type herein described. It is obvious, however, that the invention is capable of being modified to a considerable extent without departing materially from the principles of its operation. It is my intention, therefore, to include all such modifications within the scope of the appended claims.

What is claimed is:

1. A disconnecting, air break switch for high tension transmission lines comprising, in combination, a pivoted switch blade, jaws with which the blade is adapted to contact, insulators supporting said jaws and blade, said blade having a heel portion extending beyond its pivot, slidably means normally engaging said heel portion to positively hold the blade in contact with the jaws, means operable by an excessive current to retract the

first-mentioned means and release the blade, and means for automatically opening said blade as soon as it is released.

2. A disconnecting, air break switch for high tension transmission lines comprising, in combination, a pivoted switch blade, jaws with which the blade is adapted to contact, porcelain insulators supporting said jaws, said blade having a heel portion extending beyond its pivot, a reciprocable rod having a roller mounted thereon and normally engaging said heel portion to positively hold the blade in contact with the jaws, a solenoid having a core connected to said rod and operable by an excessive current to retract said rod and roller to release the blade, and means for automatically opening said blade as soon as it is released.

3. A disconnecting, air break switch for high tension transmission lines comprising, in combination, a pivoted switch blade, jaws with which the blade is adapted to contact, insulators supporting said jaws and blades, said blade having a heel portion extending beyond its pivot, slidable locking means normally engaging said heel portion to positively hold the blade in contact with the jaws, a solenoid operable by an excessive current and connected to retract said locking means and release the blade, mechanism for opening said blade, and spring actuated means for operating said mechanism as soon as the blade is released.

4. A disconnecting, air break switch for high tension transmission lines comprising, in combination, a pivoted switch blade, jaws with which the switch blade is adapted to contact, a pair of insulators supporting said blade, said blade having a heel portion extending behind its pivot, a reciprocable rod with a roller mounted thereon and normally engaging said heel portion to positively hold the blade in contact with the jaws, a solenoid having a core connected to said rod and operable by an excessive current to retract the same to move the roller out of contact with said heel portion and release the blade, mechanism for opening said blade, and spring actuated means for operating said mechanism as soon as the blade is released.

5. In a switch of the character described, the combination of an insulator mounted to oscillate about a horizontal axis, a second insulator mounted to oscillate about a vertical axis, a member supported by said insulators, a switch blade pivotally connected to said member, jaws with which the switch blade is adapted to contact, means actuated by one of said insulators, when oscillated, to open the blade, and means actuated by the other insulator, when oscillated, to close the blade.

6. In a switch of the character described, the combination of an insulator mounted to oscillate about a horizontal axis, a second insulator mounted to oscillate about a vertical

axis, a member supported by said insulators, a switch blade pivotally connected to said member, jaws with which the switch blade is adapted to contact, means movably mounted on said member and normally engaging the blade to positively hold it closed and actuated by one of the insulators, when oscillated, to release the blade, means for automatically opening the blade as soon as it is released, and means actuated by the other insulator, when oscillated, to close the blade.

7. In a switch of the character described, the combination of an insulator mounted to oscillate about a horizontal axis, a second insulator mounted to oscillate about a vertical axis, a yoke supported by said insulators and held substantially stationary while either one of the insulators is oscillated, a switch blade pivotally connected to said yoke, jaws with which the switch blade is adapted to contact, means actuated by the first-mentioned insulator, when oscillated, to open the blade, and means actuated by said second insulator, when oscillated, to close the blade.

8. In a switch of the character described, the combination of an insulator mounted to oscillate about a horizontal axis, a second insulator mounted to oscillate about a vertical axis, a yoke supported by said insulators, a switch blade pivotally connected to said yoke, jaws with which the switch blade is adapted to contact, a longitudinally disposed member reciprocably mounted on said yoke and normally engaging the blade to positively hold it closed and actuated by the first-mentioned insulator, when oscillated, to release the blade, means for automatically opening the blade as soon as it is released, and means actuated by said second insulator, when oscillated, to close the blade.

9. In a switch of the character described, the combination of an insulator mounted to rock about a horizontal axis, a second insulator mounted to oscillate about a vertical axis, a yoke supported by said insulators, a switch blade pivotally connected to said yoke, jaws with which the switch blade is adapted to contact, said blade having a heel portion extending beyond its pivot, a rod reciprocably mounted in said yoke and having a roller mounted thereon which normally engages said heel portion to positively hold the blade in contact with the jaws, a solenoid having a core connected to said rod and operable by an excessive current to retract the rod and roller and release the blade, means for automatically opening the blade as soon as it is released, other means operable, when the first-mentioned insulator is manually oscillated, to retract said rod and roller and release the blade, and means actuated by said second insulator, when oscillated to close the blade.

10. In a switch of the character described, the combination of an insulator mounted to

oscillate about a horizontal axis, a second insulator mounted to oscillate about a vertical axis, a yoke supported by said insulators, a switch blade pivotally connected to said yoke, jaws with which the switch blade is adapted to contact, means movably mounted on said yoke and normally engaging the blade to positively hold it closed, a solenoid having a core connected to said means for moving the same to release the blade, mechanism for opening said blade, spring actuated means for operating said mechanism as soon as the blade is released, other means operable manually by the oscillation of the first-mentioned insulator to move the first-mentioned means for releasing the blade, and means actuated by said second insulator, when oscillated, to close the blade.

11. In a switch of the character described, the combination of a switch blade, a pair of jaws with which the switch blade is normally in contact, a member on which the blade is pivotally supported, two insulators in supporting relation to said member, means to lock the switch blade in closed relation, and separate means automatically to open the switch when it is unlocked, one of said insulators being movable and having means to release the lock thereby permitting the switch blade to open.

12. In a switch of the character described, the combination of a switch blade, a pair of jaws with which the blade is normally in contact, a member on which the blade is pivotally supported, means movably mounted on said member and normally engaging the blade to hold it positively closed, two insulators in supporting relation to said member, one of said insulators being oscillatable about a horizontal axis and operable, when so oscillated, to actuate said means to release the blade, and means for automatically opening said blade as soon as it is released.

13. In a switch of the character described, the combination of a switch blade, a pair of jaws with which the blade is normally in contact, a member on which the blade is pivotally supported, a rod reciprocably mounted on said member and having a roller normally engaging the blade to hold the same positively in contact with the jaws, two insulators in supporting relation to said member, one of said insulators being oscillatable about a horizontal axis, means actuated by said last-mentioned insulator, when oscillated, to retract said rod and roller and release the switch blade, and means for automatically opening said blade as soon as it is released.

14. In a switch of the character described, the combination of a switch blade, a pair of jaws with which the blade is normally in contact, a member on which the blade is pivotally supported, said blade having a heel portion extending beyond its pivot, means

normally engaging said heel portion to hold the blade positively in contact with the jaws, two insulators in supporting relation to said member, one of said insulators being oscillatable about a horizontal axis, means actuated by said last-mentioned insulator, when oscillated, to retract the means which engages said heel portion and release the blade, mechanism for opening the blade, and spring actuated means for operating said mechanism as soon as the blade is released. 70 75

15. In a switch of the character described, the combination of a switch blade, a pair of jaws with which the blade is pivotally supported, said blade having a heel portion extending beyond its pivot, a rod supported by said yoke for reciprocation and having a roller mounted thereon and normally engaging said heel portion to hold the blade positively in contact with the jaws, two insulators in supporting relation to said yoke, one of said insulators being oscillatable about a horizontal axis, means actuated by said last-mentioned insulator, when oscillated, to retract said rod and roller and release the switch blade, a solenoid having a core connected with said rod, said solenoid being operable by an excessive current, independently of the oscillation of the insulator, to retract said rod and roller, and spring actuated means for opening said switch blade as soon as it is released. 80 85 90 95

16. In a switch of the character described, the combination of a plurality of switch blades arranged in a gang, each unit of the gang including a pair of jaws with which the corresponding blade is adapted to contact, a yoke to which the blade is pivoted, and a pair of insulators supporting the yoke, one of said insulators being mounted to oscillate about a horizontal axis; means operable automatically to open any one of said blades when an excessive current passes therethrough, means operable by the opening of said blade to oscillate in unison all of the insulators which are oscillatable about a horizontal axis, and means actuated by the oscillation of said insulators to open the other blades in the gang. 100 105 110

17. In a switch of the character described, the combination of a plurality of switch blades, a plurality of pairs of jaws with which the respective blades are pivoted, pairs of insulators supporting the yokes, there being one yoke and a pair of insulators for each blade, one insulator of each pair being mounted to oscillate about a horizontal axis, all of said oscillating insulators being rigidly connected to each other, a solenoid carried by each yoke, means actuated by the solenoid, when the current is excessive, to open the corresponding switch blade, means actuated by the opening of the blade to oscillate the insulators which are mounted on a 115 120 125 130

horizontal axis, and means actuated by the oscillation of said insulators to open all of the other switch blades.

18. In a switch of the character described, the combination of a pair of insulators, one of which is mounted to oscillate about a horizontal axis and the other mounted to oscillate about a vertical axis, a yoke supported by said insulators so that it will be substantially stationary when either of said insulators is oscillated about its axis, a blade pivotally mounted on said yoke, a third insulator having a pair of jaws supported thereon and cooperating with said blade, means operable by the oscillation of one of said pair of insulators to open the blade, and means operable by the oscillation of the other of said pair to close the blade.

19. In a switch of the character described, the combination of a pair of insulators, one of which is mounted to oscillate about a horizontal axis and the other mounted to oscillate about a vertical axis, a yoke supported by said insulators so that it will be substantially stationary when either of said insulators is oscillated about its axis, a blade pivotally mounted on said yoke, a third insulator having a pair of jaws supported thereon and cooperating with said blade, a solenoid operable by an excessive overload on the line to automatically open the switch blade, other means operable by the manual oscillation of one of said pair of insulators to open the switch blade, and means operable by the manual oscillation of the other of said pair to close the blade.

20. In a switch of the character described, the combination of two insulators, the first of which is mounted to oscillate about a horizontal axis toward or away from the second, the second being mounted to oscillate about a vertical axis, brackets secured to the respective insulators, a yoke supported by the brackets, a horizontal pin disposed transversely of the yoke, the bracket on the first insulator having an arcuate slot in which said pin rides when the insulator is oscillated, the bracket on the second insulator having a pin in alinement with its axis and extending upwardly through the yoke and rotatable therein, a switch blade pivoted to the yoke, a third insulator with jaws supported thereby, and means for moving said blade into or out of contact with said jaws.

21. In a switch of the character described, the combination of two insulators, the first of which is mounted to oscillate about a horizontal axis toward or away from the second, the second being mounted to oscillate about a vertical axis, brackets secured to the respective insulators, a yoke supported by the brackets, a horizontal pin disposed transversely of the yoke, a bracket on the first insulator having an arcuate slot in which said pin rides when the insulator is oscillated, the

bracket on the second insulator having a pin in alinement with its axis and extending upwardly through the yoke and rotatable therein, a switch blade pivoted to the yoke, a third insulator with jaws supported thereby with which the blade is normally in contact, means carried by the first insulator and operable, when the latter is manually oscillated away from the second insulator, to open the switch blade, and means operable by the oscillation of the second insulator to reset the switch blade.

22. In a switch of the character described, the combination of a plurality of units, each comprising a pair of insulators, the first of which is mounted to oscillate about a horizontal axis toward or away from the second, the second being mounted to oscillate about a vertical axis, brackets secured to the respective insulators, a yoke supported by the brackets, a horizontal pin disposed transversely of the yoke, the bracket on the first insulator having an arcuate slot in which said pin rides when the insulator is oscillated, the bracket on the second insulator having a pin in alinement with its axis and extending upwardly through the yoke and rotatable therein, a switch blade pivoted to the yoke, and a third insulator with jaws supported thereby with which the blade is normally in contact; said first-mentioned insulator of each unit being rigidly connected to the corresponding insulator of each of the other units, a solenoid carried by each yoke, means operable thereby whenever there is an excessive overload to open the corresponding blade, means actuated by the blade in opening to oscillate the first-mentioned insulators away from the other insulators, means operated thereby for opening the remaining blades, and means operable by the oscillation of the second insulators of each pair to reset the blades.

23. In a switch of the character described, the combination of a pivoted blade, jaws cooperating therewith, a movable member normally locking the blade in contact with the jaws, a cam pivoted to the blade, an abutment which said cam engages, means for retracting said movable member to unlock the blade, and means connected with the cam and operable as soon as the blade is unlocked to rotate said cam, bringing its thickest portion into action against said abutment to force the blade open.

24. In a switch of the character described, the combination of a pivoted blade, jaws cooperating therewith, said blade having a heel portion extending beyond its pivot, means normally engaging said heel portion to lock the blade in contact with the jaws, means operable by an excessive current to retract the first-mentioned means and unlock the blade, a cam pivoted to the blade, an abutment with which said cam engages, and means connect-

- ed with the cam and operable as soon as the blade is unlocked to rotate said cam, bringing its thickest portion into action against said abutment to force the blade open.
25. In a switch of the character described, the combination of a pivoted blade, jaws cooperating therewith, a reciprocable rod having a roller mounted thereon and normally engaging said blade to lock it in contact with the jaws, a solenoid having a core connected to said rod and operable by an excessive current to retract the rod and roller and unlock the blade, a cam pivoted to the blade, an abutment which said cam engages, means connected with the cam and operable as soon as the blade is unlocked to rotate said cam, bringing its thickest portion into action against said abutment to force said blade open.
26. In a switch of the character described, a pivoted blade, jaws cooperating therewith, a movable member normally locking the blade in contact with the jaws, a cam pivoted to the blade, an abutment which said cam engages, means operable by an excessive overload to retract said movable member and unlock the blade, a rod pivotally connected to one side of the cam, a spring acting on said rod to move it longitudinally and to rotate said cam as soon as the blade is unlocked, thereby bringing the thickest portion of the cam into action against said abutment to force the blade open.
27. In a switch of the character described, the combination of a pivoted blade, jaws cooperating therewith, said blade having a heel portion extending beyond its pivot, a reciprocable rod having a roller mounted thereon and normally engaging said heel portion to lock the blade positively in contact with the jaws, a solenoid having a core connected to said rod and operable by an excessive overload to retract said rod and roller and unlock the blade, a cam pivoted to the blade, an abutment which said cam engages, a plunger rod pivotally connected to one side of the cam and having a head thereon, a spring engaging said head and operable as soon as the blade is unlocked to move said plunger rod longitudinally to rotate the cam, thereby bringing the thickest portion of the cam into action against said abutment to force the blade open.
28. In a switch of the character described, the combination of a plurality of units constituting a gang, each unit comprising a pivoted blade, jaws cooperating therewith, reciprocable means normally engaging said blade to lock it in contact with the jaws, means operable by an excessive overload to retract said reciprocable means and unlock the blade, a cam pivoted to the blade, an abutment which said cam engages, means connected with the cam and operable as soon as the blade is unlocked to rotate said cam bringing its thickest portion into action against said abutment to force the blade open; and means actuated by the blade of any one of the units when opening to unlock all of the other blades so that said blades may also be forced open by their respective cams.
29. A disconnecting, high tension switch of the character described comprising, in combination, a pivoted switch blade, means normally biasing the blade to open, a sliding lock for the blade, movable cam means engageable with the lower edge of the blade to close the switch after the blade has been opened and remote manually operable means to move said cam means.
30. A disconnecting high tension switch of the character described comprising, in combination, a pivoted switch blade, means normally biasing the blade to open, releasable locking means for the blade, movable cam means engageable with the lower edge of the blade to close the switch after the blade has been opened and remote manually operable means to move said cam means; said cam means being free to be moved by the blade when it is released to permit it to swing open.
31. A switch of the character described comprising, in combination, a pivoted switch blade presenting a heel portion beyond the pivot, means normally biasing the blade to swing open, overload responsive means for locking the blade in closed position, movable cam means engageable beneath the heel portion of the blade to close the switch after the blade has been opened, and remote handle operating means to manually actuate said cam means; said cam means being freely movable by the switch blade when it opens.
32. In a switch of the character described, the combination of a switch blade, a pair of jaws with which the blade is normally in contact, means pivotally supporting said blade, releasable locking means engageable with said blade to hold it in closed position, and a pair of movable insulators associated with the switch; one of said insulators being operatively connected to said releasable locking means, remote manually operable means for moving said insulator; the other insulator having means engageable with the switch blade to reclose it and manually operating means to move said second named insulator.
33. In a switch of the character described, a plurality of switch blades arranged in a gang, each unit of the gang including a stationary pair of jaws with which the corresponding blade is adapted to contact, insulators having means pivotally supporting the respective blades, means connected to the respective blades normally urging them to open, solenoid operated latch means cooperating with the respective blades normally to hold them in closed position, cam means cooperating with each blade to reclose it, means

connecting said cam means to operate in unison, and manual means for moving said cam means; said cam means being freely movable by any one of said switch blades after it is released by said locking means.

5 In testimony that I claim the foregoing as my own, I have hereto affixed my signature.

TOMLINSON FORT JOHNSON, JR.
